HAND DISPENSING DEVICE FOR SMALL ELEMENTS

Eric Ischinger, Sr., Reading, Pa.

Application June 7, 1952, Serial No. 20,076

Term of patent 14 years

(Cl. D52—2)

To all whom it may concern:

Be it known that I, Eric Ischinger Sr., a citizen of the United States of America, residing at Reading, in the county of Berks and State of Pennsylvania, have invented a new, original, and ornamental Design for a Hand Dispensing Device for Small Elements, of which the following is a specification, reference being had to the accompanying drawing, forming part thereof.

Fig. 1 is a top plan view of the hand dispensing device for small elements, showing my new design.

Fig. 2 is a side elevational view of the same.

Fig. 3 is a front elevational view of the same.

Fig. 4 is a rear elevational view of the same.

I claim:

The ornamental design for a hand dispensing device for small elements, as shown.

ERIC ISCHINGER, SR.
